(57) **CLAIM**

The ornamental design for a connector, as shown and described.

DESCRIPTION

FIG. 1 is a perspective view of a connector comprising an adjustable nozzle arranged in a first position;

FIG. 2 is a perspective view of the connector comprising the adjustable nozzle arranged in the first position;

FIG. 3 is a front elevation view of the connector comprising the adjustable nozzle arranged in the first position;

FIG. 4 is a back elevation view of the connector comprising the adjustable nozzle arranged in the first position;

FIG. 5 is a right side elevation view of the connector comprising the adjustable nozzle arranged in the first position;

FIG. 6 is a left side elevation view of the connector comprising the adjustable nozzle arranged in the first position;

FIG. 7 is a top plan view of the connector comprising the adjustable nozzle arranged in the first position;

FIG. 8 is a bottom plan view of the connector comprising the adjustable nozzle arranged in the first position;

FIG. 9 is a perspective view of the connector comprising the adjustable nozzle arranged in a second position;

FIG. 10 is a perspective view of the connector comprising the adjustable nozzle arranged in the second position;

FIG. 11 is a front elevation view of the connector comprising the adjustable nozzle arranged in the second position;

FIG. 12 is a back elevation view of the connector comprising the adjustable nozzle arranged in the second position;

FIG. 13 is a right side elevation view of the connector comprising the adjustable nozzle arranged in the second position;

(Continued)

FIG. 14 is a left side elevation view of the connector comprising the adjustable nozzle arranged in the second position;

FIG. 15 is a top plan view of the connector comprising the adjustable nozzle arranged in the second position; and, FIG. 16 is a bottom plan view of the connector comprising the adjustable nozzle arranged in the second position. The broken lines in the drawings illustrate portions of the connector that form no part of the claimed design.
